UNITED STATES PATENT OFFICE

2,055,663

TYPOGRAPHICAL COMPOSING MACHINE

Richard R. Mead, Queens Village, N. Y., assignor
to Mergenthaler Linotype Company, a corpora-
tion of New York

Application September 4, 1935, Serial No. 39,112

20 Claims. (Cl. 199—46)

This invention relates to typographical machines, such as "linotype" machines of the general organization represented in Letters Patent of the United States No. 436,532 to O. Mergenthaler, wherein circulating matrices are released from a magazine in the order in which their characters are to appear in print and then assembled in line, the composed line transferred to the face of the mold, the mold filled with molten metal to form a slug or linotype against the matrices which produce the type characters thereon, and the matrices thereafter elevated and returned through distributing mechanism to the magazine from which they started.

More particularly, the present improvements deal with devices for removing a matrix magazine from its base frame when it is desired to replace such magazine with one containing a different matrix font. In the present instance, the base frame is equipped with devices normally retracted within the frame but which are adapted, upon the removal of a magazine, to be extended to a position wherein they will support the magazine in a vertical position in front of the machine clear of the frame, assembler throat, and other magazines should there be any. These magazine removal devices are confined to the limits of the base frame and are moved from retracted to extended position and returned automatically during the removal and replacement of the magazine, such movement throughout being entirely within the plane of the base frame.

The invention is particularly advantageous when used with machines employing a plurality of matrix magazines in bank, since in such cases it is unnecessary to touch or disturb any of the magazines other than that which it is desired to replace. Although the improvements have been illustrated in connection with a three magazine machine for the reasons just stated, it is apparent that they could be used with equal facility in machines employing a greater or a lesser number. It may also be added that the magazines shown herein are so-called "main magazines" although they could as well be "auxiliary magazines".

Referring to the drawings:

Fig. 1 is a side elevation of a portion of a typographical composing machine equipped with the present improvements;

Fig. 2 is a plan view of the portion of the machine shown in Fig. 1, with the magazine removal device in its extended or active position;

Fig. 3 is a front view of the portion of the machine shown in Fig. 1, with some of the parts re-

moved to show the construction of the magazine removal device;

Fig. 4 is a side elevation of a portion of a typographical composing machine equipped with another embodiment of the present invention, and showing the magazine removal device in its extended position;

Fig. 5 is a top view of the parts shown in Fig. 4, with the magazine in place and partly broken away to show the magazine removal device in retracted position, the device in its extended position being shown in broken lines;

Fig. 6 is a front view of the parts shown in Fig. 5;

Fig. 7 is a side elevation of a portion of a typographical composing machine, showing a third embodiment of the present invention and with the magazine removal device in its extended position supporting a magazine at the front of the machine;

Fig. 8 is a top view of a portion of the machine shown in Fig. 7, but with the magazine in place and partly broken away to show the magazine removal device in its retracted position, the extended and an intermediate position of the device being illustrated in broken and dotted lines respectively; and

Fig. 9 is a vertical section on line 9—9 of Fig. 8.

In the different embodiments, the matrices are stored according to font or otherwise in the magazines A, three of which are shown, but of which a greater or lesser number might be employed if desired. The several magazines are removably mounted upon separate base frames B, as by means of lips or shoulders B¹ rising from the forward or lower ends of the base frames and engaging in front of cross ribs or plates A¹ attached to the undersides of the magazines. The three base frames B are all connected by means of screws B² to a pair of side plates C, these parts thus constituting a rigid shift frame for the magazines. The shift frame is in turn mounted in a relatively fixed supporting frame D pivoted at its upper end (see Fig. 7) as at D¹, to the machine frame and resting loosely at its lower end upon adjusting screws (not shown) carried by the machine frame.

It may be stated here that the magazines herein shown are of the short variety and, for this reason there is employed in connection with the magazines, a channeled conductor E which serves to connect the active one thereof with the customary magazine entrance F leading from the distributing mechanism G. As will be noted from Fig. 7, both the magazine entrance F and

the channeled conductor E are mounted directly on the supporting frame.

In the embodiments illustrated, the magazines are each provided with a fixed bank of escape-
5 ments H adapted to be actuated in the usual way from the main keyboard but, as these parts are well known and form no part of the present invention, any further description would be superfluous. If desired, reference may be had
10 to the Kennedy Patent No. 1,561,244 for fuller information with respect to the keyboard connections. An assembler entrance I is arranged to receive the matrices as they are released from the magazines and carry them to the composing
15 or assembling mechanism.

In selecting one or another of the magazines for use, the shift frame C is raised and lowered within the fixed supporting frame D to bring the selected magazine into registration with the assembler entrance I at the front and the channeled conductor E at the back.

The mechanism for raising and lowering the magazine shift frame (see Figs. 1, 4 and 7) consists in part of a pair of cams J (only one of which is shown) arranged at opposite sides of the machine and mounted on a shaft J¹ extending horizontally beneath the magazines and journaled at its opposite ends in the supporting frame D. As the cams J are rotated, they co-operate with a corresponding pair of rollers J² carried by the shift frame C to raise or lower the latter into a position wherein the selected magazine will be operative, the shift frame during the adjustment just mentioned being guided by anti-friction rollers J³ with which the supporting frame D is equipped.

When it is desired to remove or replace a magazine, the entire supporting frame D is rocked about its pivot D¹ to raise the magazines to a position wherein the one selected for removal will clear the assembler entrance I.

The mechanism for raising the supporting frame D includes a toggle device consisting of a pair of pivotally connected members K and K¹,
45 the member K being rotatably connected to the cross shaft J¹ and the member K¹ fastened to a rock shaft K² journaled in the main frame of the machine, the arrangement being such that, as the rock shaft K² is turned to straighten out
50 the toggle members, the supporting frame D will be raised to its uppermost position wherein the removal of the magazines can be effected. The rock shaft K² is operated by a crank handle K³ arranged at the side of the machine through two
55 arms K⁴ and K⁵ and an interconnecting link K⁶, the arm K⁴ being fixed to the crank handle, and the arm K⁵ fixed to the rock shaft K², and the intermediate link K⁶ being pivotally connected at its opposite ends to said arms. If desired, the
60 pivotally mounted supporting frame D may be counter-balanced by a tension spring D² (Fig. 7) anchored at one end to the machine frame or a bracket carried thereby, and connected at its opposite end to the rear arm of a lever D³ pivotally mounted adjacent its center, and having a front arm provided with an anti-friction roller D⁴ bearing against the frame D at the bottom.
65

The parts, as thus far described, are known and constitute no part of the present improvements. For a more detailed description thereof, reference may be had to the Burt Patent No. 1,864,799.

In order to remove a magazine from a machine equipped with the improvements illustrated in Figs. 1, 2 and 3, the magazine supporting frame

D is first raised to position the magazine selected for removal above or clear of the assembler entrance I. The supporting frame D in its raised position is illustrated in Fig. 1, and there it will be observed that the topmost magazine (which, for the setting of the cam J as shown, would in its normal position register with the assembler entrance I) has been elevated to clear the assembler entrance, so that the magazine may readily be removed in a forward direction. The magazine is then lifted slightly until the cross rib A¹ clears the shoulders B¹ on the associated base frame B, whereupon the magazine may be slid forwardly in its own plane until another cross rib A², fixed to the underside of the magazine and rearwardly of the center of gravity thereof, engages a cross piece L secured at the front end of a pair of telescoping slides L¹, L² carried by the base frame B. As the magazine is drawn forwardly, the slides L¹ and L² will be extended as shown in Fig. 2, and, as the magazine leaves its base frame B, it thereafter will receive its sole support from the slides which, when fully extended, will position the cross piece L so that the magazine supported thereby can be swung into a vertical position (see Fig. 1) clear of the assembler entrance I and likewise clear of the remaining magazines in the bank (this whether the magazine be the top one or a lower one).

In its vertical position, the magazine A is held on the cross piece by a pair of brackets A³ riveted at their centers to the cross rib A² and at their rear ends to a similar cross rib A⁴ likewise fastened to the underside of the magazine at the rear edge thereof. The brackets A⁴ (which in 35 the retracted position of the slides are housed in recesses B² formed in the supporting frame B) have forwardly extending portions that pass under the cross piece L as the magazine is drawn from its base frame. The brackets A⁴ 40 are spaced apart so as to engage the cross piece L at its ends *l* which are partly cut away for clearance, and rounded off to facilitate rotating the magazine to its vertical position. The rounded portions extend inwardly from the outer 45 ends of the cross piece and terminate at the body portion proper of the slide L¹, and also project somewhat above the upper face of the slide to present abutments against which the cross rib A² on the magazine engages to effect the 50 extension of the slides as previously described.

When the magazine is hanging on the cross piece L in its vertical position, it is a simple matter to remove it and substitute another magazine for replacement in the machine. 55

ments and which seats in a complementary recess L⁸ formed in the upper face of the slide L². The slide L² and the base frame B are respectively formed with a similar boss L⁹ and recess B³ for 5 the same purpose.

The fore-and-aft movement of the top slide L¹ with respect to the bottom slide L² and of the bottom slide with respect to the frame B is limited by two sets of gibbs l¹ and l², the set l¹ being 10 fastened to the bottom slide L² and extending into a pair of recesses l³ formed in the opposite edges of the slide L¹ and terminating short of the ends thereof so as to present shoulders which bank against the gibbs, and the other set l² being 15 fastened to the plates L⁵ on the base frame and extending into a similar pair of recesses l⁴ formed in the opposite edges of the bottom slide L², and which likewise terminate short of the ends of the slide L² to present shoulders cooperating 20 with the gibbs l² for the same purpose.

It might be stated here that the portion of the base frame presenting the bearing surface for the bottom slide L² is formed in two parts, the rear part being integral with the frame proper 25 and the front part being constituted by a plate B⁴ secured to the frame at the bottom in recesses provided for the purpose and extending beyond the front edge of the frame so as to give additional support to the sliding members L¹ and L².

30 In order to replace a magazine, it is first hung upon the cross piece L by means of the brackets A³ and thereafter tilted about the cross piece into the plane of its base frame. The magazine is then pushed rearwardly until the cross piece A¹ 35 thereon seats behind the shoulders B¹ formed on the base frame.

During the rearward movement of the magazine, the cross piece L remains in its magazine supporting position until the magazine at its 40 rear edge rests upon the base frame, whereupon a pair of angular-shaped brackets A⁶, secured to a cross rib A⁷ on the underside of the magazine, will engage the cross piece L and cause the retraction of the slides L¹ and L² within the base frame 45 as the magazine is pushed home to its proper position on the base frame. When the magazine is in its proper position, the angular-shaped brackets A⁶ just referred to, project into recesses B⁵ formed in the bottom face of the plate B⁴, such 50 recesses having sufficient depth to provide the necessary clearance for the brackets when the magazine is raised to clear the shoulders B¹ at the front of the supporting frame.

The telescoping slides L¹ and L² are held yielding- 55 ingly in normal position within the base frame B by two pairs of leaf springs l⁵ and l⁶, the pair l⁵ being screwed to the base frame and adapted to engage in notches l⁷ formed at the front edge of the bottom slide member L², and the other pair l⁶ 60 being screwed to the bottom slide member and adapted to engage in notches l⁸ formed in the bottom face of the top slide member L¹ (see Figs. 1 and 2). It will be noted that both the base frame and the bottom slide member, directly beneath 65 the leaf springs, are recessed as at l⁹, so as to provide clearance for the latter during the forward and return movement of the slides.

In the second embodiment illustrated in Figs. 4 to 6, the devices for supporting the magazine 70 in its forward vertical position, instead of being telescopic, comprise a pair of angular-shaped pivoted member M M¹, movable in the plane of the base frame B.

The members M, M¹ are pivoted one at each 75 side of the base frame on hinge lugs M² formed

as an integral part of the end sections, as well as the main body portion of the frame, the lugs being somewhat thicker than the body portion in order to provide the necessary strength. The members M and M¹ are formed with short rear 5 arms m which bear against the underside of the base frame, and longer front arms m¹ which extend inwardly and cross each other at the center of the base frame, the arm of the left-hand member M being offset so as to clear the corresponding arm of the right-hand member M¹. The bearing surface presented by the frame and the large hinge lugs to the members M and M¹ is further augmented by plates m² riveted one to each of the arms m¹ adjacent the hinge lugs and 10 which have portions bearing on the top face of said lugs, segmental portions of which are cut away to provide clearance. The arms m¹ are further provided at their front extremities with members m³ riveted to the arms and which present 15 upstanding lugs m⁴ terminating just below the underside of the matrix magazine.

Now in order to remove a magazine from the base frame, it is first raised slightly to permit the cross rib A¹ on the underside thereof to clear 25 the shoulders B¹ on the base frame, whereupon the magazine may slide forwardly as in the embodiment previously described. As it does so and prior to the time that it leaves the base frame, a pair of plates A¹⁰ fastened to a cross rib A² on 30 the magazine will engage the lugs m⁴ and cause the members M and M¹ to swing in the plane of the base frame from the position shown by the solid lines in Fig. 5 to the position shown by the broken lines therein, in which latter position the 35 magazine will be supported solely by said members. In the extended position of the members M and M¹, the magazine (even though it be a lower one) will clear the other magazines in the bank and can be rotated into the vertical position 40 shown in Fig. 4, where it is sustained by the engagement of the plates A¹⁰ with the lugs m. In this position, the magazine may be readily removed and a different one substituted therefor.

The extended positions of the members M and 45 M¹ are determined by a pin m⁵ which passes through slots m⁶ formed in said members and having sufficient length to permit free movement of the members M and M¹ between their retracted and extended positions. Furthermore, the pin 50 m⁵ is provided at its opposite ends with heads m⁷ that engage the top and bottom faces of the members M and M¹ respectively and serve to hold them together so as to act as a unit in supporting the magazine. In the retracted position of 55 the supporting members, the pin will rest rearwardly of the front edge of the base frame, the center rib of which is recessed as at m⁸, to give the necessary clearance (see Fig. 5).

It may be noted that the plates A¹⁰ project for 60 a short distance forwardly of the cross rib A² and, due to the thickness of the latter, the extended portions will be spaced somewhat from the underside of the magazine, thereby permitting the lugs m⁴ on the arms m¹ to engage behind the 65 plates so as securely to support the magazine when in its vertical position. Furthermore, the plates A¹⁰ are of sufficient length to insure engagement with the lugs m⁴ throughout the movement of the arms m¹ from their normal retracted position to their fully extended position.

In order to replace a magazine on the base frame, it is first placed in a vertical position on the members M and M¹, then tilted into the plane 70 of the base frame, and thereafter pushed rear- 75

wardly, the members remaining in their extended position until after the rear edge of the magazine has passed beyond the front edge of the frame for a short distance, whereupon another cross rib 5 A¹¹ secured at the underside of the magazine will engage the lugs n⁴ on the members and swing them back to their normal retracted positions within the frame.

The magazine is guided in its movement on the 10 base frame by a fore-and-aft bar A¹² (Figs. 5 and 6) riveted to the magazine cross ribs and which slides in a guideway formed in the center rib of the base frame.

The third embodiment illustrated in Figs. 7, 8 15 and 9 is similar to that shown in Figs. 4, 5 and 6, in that there are provided two members N and N¹ pivotally mounted adjacent the lateral edges of the base frame and movable in the plane thereof from a retracted position within the frame to an 20 extended position out of the frame where the magazine is supported in a vertical position clear of the assembler throat and the other magazines in the bank. In this instance, however, the members N and N¹ are formed with arm portions 25 n and n¹ meeting at the center of the base frame when the members are in their normal or retracted positions, and are also formed at their inner ends with arcuate portions n² and n³ extending to the rear edge of the base frame and provided in their adjacent edges with complementary gear teeth n⁴ which cause the members N and N¹ to move in unison. The members N and N¹ have a bearing on the body portion 30 proper of the base frame, which for this purpose is formed with arcuate ribs B¹⁰ corresponding to the arcuate portions n², n³ of the members, and said members are held slidably against the bearing surfaces by anti-friction rollers n⁵ mounted on pins n⁶ fixed in the base of the frame, the 35 rollers seating in recesses n⁷ formed in the edges of the arcuate portions n², n³ opposite the edges that present the teeth (Figs. 8 and 9).

When the members N and N¹ are in their retracted position, the rear edges of the arm portions n, n¹ thereof bank against the rollers n⁵, whereas when they are in their extended position, lugs n⁸ formed at the outer ends of the arcuate portions n² and n³ bank against the pins n⁶, it 40 being in this manner that the retracted and extended positions of the members are determined.

The magazine on its underside and at the rear edge is provided with a cross rib A²⁰ extending the full width of the magazine, and at a short distance forward of said rib there is also provided 45 another cross rib A²¹, to which latter there are secured two plates A²² presenting overhanging portions for a purpose presently to be described. The magazine further is equipped with a center bar A²³ fastened to both cross pieces A²⁰ and A²¹ 50 and extending toward the front of the magazine somewhat beyond the front edge of plates A²² just alluded to.

In order to remove a magazine from the base 55 frame, it is lifted to clear the shoulders B¹ formed thereon, as in the embodiments previously described, and allowed to slide forwardly, and shortly after it starts its forward movement, the center bar A²³ at its front end will engage a pair of shoulders n⁹, formed one on each of the arcuate portions n² and n³ in the edges thereof that carry the teeth. As the magazine continues in its 60 movement, said center bar will rotate the members N and N¹ from the position shown by the solid lines in Fig. 8 to that shown by the dotted lines therein, which is just about half the full

range of their movement. The magazine will now move a small distance by itself, but shortly thereafter the plates A²² will engage a pair of lugs n¹⁰ formed one at each of the inner ends of the straight arm portions n, n¹ of the members N 5 and N¹ and, as the magazine continues to move forwardly, said plates will effect the movement of said members to the position shown by the broken lines in Fig. 8. In this final position, the members are fully extended and the magazine can be 10 swung to a vertical position in front of the assembler throat, the lugs n¹⁰ engaging behind the plates A²² to hold the magazine suspended. With the magazine suspended in this manner, it is a simple matter to remove it and replace it by another containing a different font. 15

In order to replace a magazine on the base frame, it is first suspended in a vertical position on the members N and N¹, then tilted into the plane of the base frame, and thereafter pushed 20 rearwardly, the members remaining in their extended position until after the rear edge of the magazine has passed beyond the front edge of the supporting frame, whereupon the cross rib A² on the underside of the magazine will engage the 25 lugs n¹⁰ and return the members to their normal retracted position within the base frame. Since the lugs n¹⁰, in the retracted position of the members N and N¹, stand to the rear of the shoulders B¹, the cross rib A² in this instance is 30 made wider in its center region in order that the members will have been returned fully to their normal position when the cross rib A² engages behind the shoulders B¹ on the base frame. 35

It may be stated that the shoulders n⁹, against 40 which the center bar A²³ banks to effect the first part of the extending movement of the members N and N¹, are presented at the front ends of a pair of recesses n¹¹ formed in the opposed edges of the arcuate portions n² and n³ just above the 45 teeth n⁴ and which are present to provide clearance for the center bar during its movement.

It will be noted, as to each of the three different embodiments shown and described, that 50 the operation of the magazine removal devices is entirely automatic, the operator in removing a magazine from its base frame proceeding as if the removal devices were not present. Thus, in removing a magazine, the operator grasps the magazine at its lower end and, after disengaging 55 it from the stop shoulders on the base frame, slides it straight forwardly along the base frame, just as he does in existing machines, paying no attention whatever to the magazine removal devices which, as a matter of fact, are inaccessible 60 and entirely concealed from view. The first or initial movement of the magazine is entirely free and of considerable extent, but thereafter the magazine picks up the removal devices and pulls them out of the frame to their extended position, the magazine being supported by the base frame throughout its whole sliding movement until just near the end of such movement, when the rear end of the magazine passes beyond the lower or forward end of the base frame; at this 65 time, the removal devices have assumed their fully extended position and no further sliding movement of the magazine is permitted, so that the magazine is then allowed to assume its vertical position in front of the assembled entrance 70 where it can be handled with ease. Similarly, in replacing the magazine upon the base frame, the magazine is first tilted from its vertical position back into its normal inclined position and then slid straight-rearwardly until it assumes its 75

proper position on the base frame. Here again, the first or initial part of this rearward movement of the magazine is free or relative to the magazine removal devices, these devices being picked up by 5 the magazine in its continued rearward movement and restored to their normal or retracted position within the base frame by the final part of such movement. This differential movement of the magazine and its removal devices aids in 10 keeping these devices confined wholly within the limits of the base frame, which is an important feature and especially in a movable multiple magazine machine, such as shown, wherein the base frames must be moved upwardly and down- 15 wardly with reference to contiguous parts to bring any selected magazine into operative position. In this connection, it will be understood of course that, in each of the embodiments illustrated, all the base frames will be equipped with 20 magazine removal devices, the description given applying to them all and not being limited to one frame only.

In the accompanying drawings the invention has been shown merely by way of example and in 25 preferred form, and obviously, many variations and modifications may be made therein which will still be comprised within its spirit. It is to be understood, therefore, that the invention is not limited to any specific form or embodiment, 30 except insofar as such limitations are specified in the appended claims.

Having thus described my invention, what I claim is:

1. In a typographical composing machine, the 35 combination of a supporting frame, a removable matrix magazine supported thereon, and magazine removal means arranged normally within the confines of the supporting frame and movable in the plane of the frame into a magazine supporting position outside the confines of the frame.

2. A machine according to claim 1, wherein the magazine is provided with devices for actuating the magazine removal means during its removal,

3. In a typographical composing machine, the 45 combination of a supporting frame, a removable magazine supported thereon, magazine removal means arranged normally within the confines of the supporting frame and adapted as the magazine is removed to be moved in the plane of the frame into a magazine supporting position outside the confines of the frame, and devices for restoring said means to normal position upon the replacement of a magazine.

4. In a typographical composing machine, the 55 combination of a supporting frame, a removable magazine supported thereon, means mounted within the frame and positionable during the removal of the magazine to support the latter clear of the frame, and devices attached to the magazine and cooperating with said means to permit the magazine during removal to be supported by said means in a vertical position.

5. A typographical composing machine according to claim 4, wherein the magazine is 65 further provided with other devices for restoring said means to normal position upon the replacement of the magazine.

6. A typographical composing machine according to claim 4, wherein the means referred 70 to are confined within the limits of the magazine supporting frame when in normal position.

7. In a typographical composing machine, the 75 combination of a supporting frame, a removable matrix magazine supported thereon, means arranged normally within the confines of the sup-

porting frame and adapted to be actuated during the removal of the magazine into position for supporting the magazine clear of the frame, said means including devices about which the magazine may be turned to vertical position, and 5 means on the magazine for engaging said devices to hold the magazine detachably on the supporting means when thus vertically positioned.

8. A combination according to claim 7, where- 10 in the magazine is also provided with devices for returning the supporting means to normal position as the magazine is replaced.

9. In a typographical composing machine, the 15 combination of a supporting frame, a matrix magazine supported thereon and removable therefrom by an endwise movement with respect thereto, and means movable in the plane of the frame for supporting the magazine clear of the frame, said means permitting a free initial move- 20 ment of the magazine during removal and then being actuated to magazine supporting position by the continued movement of the magazine.

10. A combination according to claim 9, where- 25 in the supporting means are returned to nor- mal position automatically upon the replacement of a magazine.

11. In a typographical composing machine, the 30 combination of a supporting frame, a removable magazine supported thereon, and means mount- 35 ed in the frame and actuated automatically during the removal of the magazine into a position for supporting the magazine clear of the frame.

12. In a typographical composing machine, the 40 combination of a supporting frame, a removable magazine supported thereon, means mounted in the frame and movable in the plane thereof for supporting the magazine during removal, and devices operable as the magazine is removed for automatically actuating said means from an in- 45 active position within the frame to an active position out of the frame.

13. In a typographical composing machine, the 50 combination of a supporting frame, telescoping devices mounted in said frame and movable in the plane thereof, a removable matrix magazine supported on said frame independently of the telescoping devices, and means operable during the removal of the magazine to move said telescoping devices into their extended position for supporting the magazine clear of the frame.

14. A combination according to claim 11, 55 wherein the telescoping devices include a trans- verse member, and wherein the magazine is equipped with means cooperating with said member to effect the positioning of said devices and to support the magazine vertically on the trans-verse member when the magazine is clear of the frame.

15. A combination according to claim 11, 60 wherein resilient means are provided for re- leasesably holding the telescoping devices in nor- mal position within the magazine supporting frame.

16. In a typographical composing machine, the 65 combination of a supporting frame, a removable magazine supported thereon, and a pair of maga- zine supporting arms pivotally mounted in the frame, one at each side thereof, and movable in the plane thereof from an inactive position 70 within the frame to an active position out of the frame.

17. A combination according to claim 16, 75 wherein means are provided for effecting the simultaneous movement of the pivoted arms.

18. A combination according to claim 16, wherein the magazine is provided with means for automatically moving the pivoted arms from inactive to active position as the magazine is removed from the frame.
19. A combination according to claim 16, wherein the magazine is provided with means both for moving the pivoted arms to active position out of the frame as the magazine is removed and for returning the pivoted arms to inactive position within the frame as the magazine is replaced.
20. A combination according to claim 16, 5 wherein the pivoted arms are geared together to effect simultaneous movement thereof.

RICHARD R. MEAD.
